UNITED STATES PATENT OFFICE.

CHARLES D. SEEBERGER, OF NEW YORK, N. Y., ASSIGNOR TO OTIS ELEVATOR COMPANY, A CORPORATION OF NEW JERSEY.

CONVEYER.

1,014,100.

Specification of Letters Patent. Patented Jan. 9, 1912.

Application filed January 20, 1903, Serial No. 139,774. Renewed February 27, 1905. Serial No. 247,539.

To all whom it may concern:

Be it known that I, CHARLES D. SEEBERGER, a citizen of the United States, residing at New York, in the county of New York and State of New York, have invented certain new and useful Improvements in Conveyers, (Case No. 15,) of which the following is a specification.

My present invention is concerned with certain improvements in conveying apparatus, such as traveling stairways, and is designed to produce a device of the class described in which the track, as it were, shall be movable instead of stationary, as these devices have been hitherto constructed. Instead of supplying the steps or carriers with wheels which roll on stationary tracks, I provide bearing surfaces on said steps or carriers which contact with and are carried forward by suitable rollers mounted in stationary bearings and driven at a rate of speed in which the horizontal component of movement of the steps is uniform on the different portions so that the chain of steps or carriers will be moved forward continuously and evenly on the horizontal landings as well as the inclined ascents and descents.

Another feature of my invention is a system of connections between the steps by which the customary swinging links heretofore employed may be dispensed with, and the steps connected directly to each other by slotted pin connections so that they coöperate directly with each other and with the tracks upon which they move so as to be held thereby in position with their tread surfaces horizontal and uppermost on the landings and inclines without the employment of some form of the parallel linkage system heretofore considered essential for this class of devices.

My invention is further concerned with a traveling stairway system in which the steps in passing from the horizontal to the inclined portions move vertically upward in a straight line relative to the adjacent steps instead of in a curved line as necessitated by the constructions heretofore employed. By this mechanism I am enabled to employ a straight rigid riser instead of the curved one which has been heretofore necessary in order to prevent any divergence between the nose of one step and the riser of the step in advance of it in passing from the inclined portions to the horizontal.

To illustrate my invention, I annex here-

to five sheets of drawings, in which the same reference characters are used to designate identical parts in all the figures, of which—

Figure 1 is a side elevation, somewhat diagrammatic in its nature, of the upper end and landing of a system embodying my present inventions; Fig. 2 is a similar view of the lower end; Fig. 3 is a horizontal section on the line A—A of Fig. 2; Fig. 4 is a similar view on the line B—B of Fig. 2; Fig. 5 is a similar view in section on the irregular line C—C of Fig. 1; Fig. 6 is a similar view on the line D—D of Fig. 2; and Fig. 7 is a view of a portion of the structure shown in Fig. 1, on an enlarged scale, and with the parts in a different position.

The system is supported between the structural plates 10, shown in Figs. 3, 4 and 5, which may have the angle iron strips 11 along the upper and lower edges thereof. The steps are composed of the tread surfaces 12, with which the straight risers 13 may be integral, the angular side pieces 14, and the bearing flanges 15, the function and structure of which will be more fully explained elsewhere. The side pieces 14 are provided with the elongated vertical slots 16, with which the rods 17 extending inwardly across the step between the offset ears 18 constituting the forward angles of the side pieces 14, coöperate. The lower edges 19 of the side pieces 14 are preferably beveled to coöperate with the correspondingly grooved peripheries of the supporting and driving wheels 20.

It will be apparent that instead of employing the beveled edges of the side pieces, and grooved peripheries of the driving wheels, I might use rack teeth on the bottom of the side pieces 14 and coöperating gear teeth on the peripheries of the wheels 20. These wheels 20 are disposed in a line at an angle to the horizontal corresponding with the angle it is desired to give to the ascending portion of the steps, and are mounted to rotate on bracket bearings 21 projecting inwardly from the plates 10. These wheels 20 are preferably spaced apart uniform distances, which are, as seen in Fig. 2, slightly less than the length of the under side of one of the steps, so that each step is during a portion of the time supported by two wheels on each side. To drive these wheels 20 in unison, I preferably employ the

worm gears 22 rigidly secured thereto, which are driven by the worms 23 secured on the shaft 24 mounted in the bearings 25 suitably supported by extensions from the 5 plates 10. The shaft 24 is connected by the universal joint 26 with the horizontal shaft 27, which is also mounted in suitable bearings and forms a part of the armature shaft of the driving motor 28 supported on the 10 cross beams 29 between the plates 10. The horizontal shaft 27 is provided with a plurality of worms 30, which mesh with worm gears 31, which it will be noticed are slightly larger in diameter than the worm gears 22, 15 and which are rigidly secured to the wheels 32 which are similar to the wheels 20, but which are designed to coöperate with the steps on the upper landing, and have their grooved or toothed peripheries coöperating 20 with the bevels or toothed bearing edges 33 of the previously mentioned supporting flanges 15. As the wheels 20 coöperate with the hypotenuse of the right angled triangle formed by the steps while the wheels 32 co- 25 operate with the sides thereof, it is necessary to rotate the wheels 20 at a proportionately greater peripheral velocity than the wheels 32, for which reason it will be observed that the worm gears 31 are of proportionally greater diameter than the worm 30 gears 22 so that the wheels 32 are rotated at a proportionately slower peripheral velocity than the wheels 20.

While all of the rollers 20 and 32 for the 35 ascending run are shown and described as driven, it is obvious that this need not necessarily be so, but that some of these rollers may be idlers and merely employed to support the steps.

40 To carry the steps around the ends, I provide the spiders 34 at the lower end and the similar spiders 35 at the upper end. These spiders are mounted on shafts journaled in suitable bearings provided in the 45 plates 10, and have the yokes 36 at their ends in the right position and shape to co-operate with the rods 17 extending across the forward ends of the steps and rising and falling in the slots 16 previously referred 50 to and in the corresponding slots 38 formed in the bearing brackets 15. The positions assumed by the steps in passing around the ends as they are carried by these spiders are clearly shown in Figs. 1 and 2 and needs 55 no further explanation. The spiders are driven by the worms 39 and 40 formed on the outer ends of the shafts 24 and 27, respectively, and meshing with the worm gears 41 and 42 secured on the shafts on 60 which the spiders are mounted. The worms 39 and 40 are, as seen, of finer pitch than the worms 23 and 30, and the pitch of the worms and the diameters of the worm gears 41 and 42 are properly proportioned so that 65 the steps will be carried around the ends

at the rate of speed corresponding to their movement on the inclined and horizontal portions.

As the steps descend on the incline, they are supported by the antifriction rollers 43, 70 which preferably have their peripheries grooved in a curve, and are supported by the brackets 44 secured to the sides of the plates 10. The steps are supported on these rollers 43 during their descent by means of the 75 correspondingly grooved bearing edges 45 projecting downwardly (during the descent) from the outer edge of the flange 46 projecting from the side pieces 14 parallel to the bearing edges 19. The steps are also 80 supported, but preferably not driven, on the lower horizontal landing by means of the rollers 47 journaled upon suitable pintles 48 projecting inwardly from the plates 10 and coöperating with the same horizontal bearing portion 33 on the brackets 15 that the wheels 32 coöperate with. To prevent the lifting of the chain of steps at the lower landing where they pass from the landing to the incline, I provide on each side the 85 antifriction rollers 49 which are journaled on bearing studs 50 projecting inwardly from the plates 10, and coöperating with the upper surface of the flange 46 as clearly 90 shown in Fig. 2. To support the steps on the under side from the time they are freed from the spider 35 until they are supported by the wheels 43, I provide a set of rollers 51, 95 preferably having their peripheries grooved, and supported by the brackets 52, best shown in Fig. 5, projecting inwardly from the plates 10, and coöperating with the bearing edge 53 formed on the under surface (in that position) on the flange 54 projecting from the outer sides of the brackets 15 immediately adjacent to and parallel to the bearing surfaces 33 thereof.

To lift the step just passing into the horizontal upper landing, after it has passed beyond the uppermost of the wheels 20, I 110 provide the cam mechanism best shown in Figs. 1, 5 and 6, where it will be seen that I provide a shaft 55 journaled in suitable bearings in the plates 10, and having the worm gears 56 thereon in the position to be engaged by the worms 57 on the shaft 27. Located on the shaft 55 in the plane of the plates 15 are two cams 58, preferably having the grooved peripheries and coöperating with the bearing surfaces 33 on the plates 15. The position of the cam at the time that the step is released from the uppermost wheel 20 and is ready to be supported and raised by the cam is shown in Fig. 7, and it will be apparent that the continued movement of the cam from the position shown in that figure to that shown in Fig. 1 will 115 serve to advance the step and at the same time raise it to the necessary level to be carried to and caught by the first wheel 32 of 120 125 130

the series. The cam 58 has the latter portion of its periphery, from the points 59 to 60, concentric so that the step is merely carried forward during this time until it is caught by the first wheel 32 of the series. The size and pitch of the worm 57 is so related to the worm gear 56 that the shaft 55 is given one complete rotation during the interval of time occupied by the movement of a step 10 through its horizontal length on the landing.

The supporting rollers constitute a way providing inclined and horizontal end portions, so that the steps are in stair formation on the incline but have their treads in horizontal planes on the horizontal portions to 15 form end landings.

By the structure herein shown and described, it will be apparent that I have produced a device in which the necessity of 20 employing wheels or shoes on each step or carrier is entirely obviated, and also one in which the connections between the steps for holding them in position with their tread surfaces horizontal on the landings and on 25 the ascending inclines is of the simplest possible character.

While I have shown and described my invention as embodied in the form which I at present consider best adapted to carry out 30 its purposes, it will be understood that it is capable of modifications, and that I do not desire to be limited in the interpretation of the following claims, except as may be necessitated by the state of the prior art.

35 What I claim as new, and desire to secure by Letters Patent of the United States is—

1. In a device of the class described, a series of moving steps, and driving members providing a way having inclined and horizontal portions and by which the steps are supported.

2. In a device of the class described, a series of moving steps, and rotating members supporting and constituting the drive 45 for the steps and providing a way having inclined and horizontal portions.

3. In a device of the class described, a series of moving steps, a way having inclined and horizontal portions, and rotating 50 members located at intervals upon the way for driving and supporting the steps.

4. In a device of the class described, a conveyer having inclined and horizontal portions and consisting of a connected series of 55 moving steps, and rotating driving members for the steps constituting the supports therefor and arranged to form a horizontal and inclined way.

5. In a device of the class described, a connected series of moving steps, rotating members mounted in fixed bearings along a way having inclined and horizontal portions and providing the support for the steps, and means for driving the steps.

65 6. In a device of the class described, the

combination with the steps or carriers moving on an inclined way, of the driving members therefor constituting tracks.

7. In a device of the class described, the combination with the steps or carriers moving on an inclined way, of the rotating driving members therefor constituting tracks 70

8. In a device of the class described, the combination with the steps or carriers moving on an inclined way, of the plurality of driving members therefor constituting tracks 75

9. In a device of the class described, the combination with the steps or carriers moving on an inclined way, of the plurality of 80 rotating driving members therefor constituting tracks thereof.

10. In a device of the class described, the combination with the steps or carriers, of 85 the plurality of driving members therefor constituting the tracks thereof and arranged on different angles so that the steps form horizontal landings and inclined stairs, and means for moving said driving members at 90 different rates of speeds on the different angles.

11. In a device of the class described, the combination with the steps or carriers, of 95 the plurality of rotating driving members therefor constituting the tracks thereof and arranged at different angles so as to form horizontal landings and inclined ascents, and means for rotating said driving members at different peripheral velocities on the 100 different angles for the purpose described.

12. In a device of the class described, the combination with the steps or carriers, of the plurality of driving members therefor constituting the tracks thereof and arranged on 105 different angles so as to form horizontal landings and inclined ascents; a single source of driving power, and connections between said source of driving power and the driving members whereby the driving members are 110 driven at different rates of speeds on the different angles for the purpose described.

13. In a device of the class described, the combination with the steps or carriers, of the plurality of rotating driving members therefor constituting inclined and horizontal tracks thereof, a single source of driving power, and connections between said source of driving power and the various driving members whereby the latter are driven at 115 different rates of peripheral velocity on said different angles.

14. In a device of the class described, the combination with the chain of connected steps or carriers, of the rotating driving 125 wheels upon which said steps are mounted, and means for driving said wheels.

15. In a device of the class described, the combination with a series of connected steps or carriers adapted to form upper and lower 130

landing portions and an intermediate inclined portion, of driving wheels by which the steps or carriers are supported and moved, said driving wheels being mounted in stationary bearings, and means for driving said wheels.

16. In a device of the class described, the combination with the chain of connected steps or carriers, of the rotating driving wheels upon which said steps are mounted, worm gears connected to said wheels, a common shaft provided with a plurality of worms meshing with said gears, and means for rotating said shaft.

15 17. In a device of the class described, the combination with the chain of connected steps or carriers, of the rotating driving wheels upon which said steps are mounted, said wheels being arranged on different angles so that the steps form horizontal landings and inclined stairs, worm gears connected to said wheels, a shaft extending along said inclined and horizontal portions and having universal joints at the angles thereof, and worms on said shaft meshing with the worm gears, the relationship between the worms and the gears being arranged so that the peripheral velocity of the driving wheels on the inclined portion varies with relation to the peripheral velocity of the driving wheels on the horizontal portion as the length of the inclined portion of the step varies with the horizontal portion thereof.

30 35 18. In a device of the class described, the combination with the steps or carriers, of the driving wheels upon which said steps are mounted, means for rotating said wheels to drive the steps, and spiders to carry said steps around the ends.

40 45 19. In a device of the class described, the combination with the steps or carriers, of the driving wheels upon which said steps are mounted, spiders to carry said steps around the ends, and means for rotating said wheels and spiders to drive the steps.

50 55 20. In a device of the class described, the combination with the steps or carriers, of the driving wheels upon which said steps are mounted, spiders to carry said steps around the ends, worm gears on the hubs of said wheels and spiders, and a shaft provided with suitably proportioned worms for meshing with said worm gears to drive the steps.

60 65 21. In a device of the class described, the combination with the steps or carriers, of the driving wheels upon which said steps are mounted, said wheels being arranged at different angles so that the steps form horizontal landings and stairs, means for rotating said wheels at the proper rates of speed to drive the steps, and spiders to carry said steps around the ends.

70 75 80 85 90 95 100 105 110 115 120 125 130 22. In a device of the class described, the combination with a series of steps or carriers

adapted to form horizontal landing portions at different levels and an intermediate inclined portion, of wheels at the landings and inclined portions carrying and driving the steps, and means for driving said wheels.

23. In a device of the class described, the combination with the steps or carriers, of the driving wheels upon which said steps are mounted, said wheels being arranged at different angles so that the steps form horizontal landings and stairs, spiders to carry said steps around the ends, and means for rotating said wheels and spiders at the proper peripheral velocities to drive the steps.

24. In a device of the class described, the combination with the steps or carriers, of the driving wheels upon which said steps are mounted, said wheels being arranged at different angles so that the steps form horizontal landings and stairs, spiders to carry said steps around the ends, worm gears secured to said wheels and spiders, and a shaft provided with worms meshing with said gears, the various worms and gears being properly proportioned to carry said steps forward at a proper rate of speed throughout their course.

25. In a device of the class described, the combination with the steps or carriers, of the rotating driving members constituting the tracks thereof and arranged to carry said steps upward on an incline, and means for supporting said steps on the return run.

26. In a device of the class described, the combination with the steps or carriers, of the rotating driving members constituting the tracks thereof and arranged to carry said steps upward on an incline, and means for supporting said steps on the return run consisting of sheaves over which portions of said steps pass.

27. In a device of the class described, the combination with the steps or carriers provided with the inclined and horizontal bearing edges and the bearing flanges parallel and adjacent thereto, of the driving wheels arranged at different angles so that the steps form horizontal landings and stairs, the inclined bearing edges coöperating with the driving wheels on the incline and the horizontal bearing edges coöperating with the driving wheels on the horizontal, sheaves on the return run with which the bearing flanges coöperate, and means for rotating the driving wheels.

28. In a device of the class described, the combination with the steps or carriers provided with the inclined and horizontal bearing edges and the bearing flanges parallel and adjacent thereto, of the driving wheels arranged at different angles so that the steps form horizontal landings and stairs, the inclined bearing edges coöperating with the driving wheels on the incline and the horizontal bearing edges coöperating with

the driving wheels on the landing portions, spiders to carry said steps around the ends of the course, sheaves on the return run with which the bearing flanges coöperate, and 5 means for rotating the driving wheels and spiders at the proper relative rates of speed.

29. In a device of the class described, the combination with the steps or carriers provided with the inclined and horizontal bearing edges and bearing flanges parallel and adjacent thereto, of the driving wheels arranged at different angles so that the steps form horizontal landings and stairs, the horizontal bearing edges coöperating with 10 the driving wheels on the landings and the inclined bearing edges coöperating with the driving wheels on the incline, sheaves on the return run with which the bearing flanges coöperate, spiders to carry said steps 15 around the ends, worm gears connected to said driving wheels and spiders, and a shaft provided with worms meshing with said worm gears, said worms and gears being properly proportioned to drive the steps at 20 the proper relative rates of speed throughout the entire course.

30. A step having a plurality of extended bearings operative in different planes of travel, and driving members therefor constituting the tracks.

31. A step having a plurality of extended bearing surfaces at each end operative in different planes of travel, and driving members therefor constituting the tracks.

32. A step having angularly disposed bearing surfaces in different vertical planes and respectively operative while the step is moving in different planes of travel, and driving members therefor constituting the 35 tracks.

33. A step having inclined and horizontal bearings operative while the step is moving in horizontal and inclined planes, respectively, and driving members therefor constituting the tracks.

34. In a device of the class described, a connected series of steps having inclined and horizontal bearing surfaces in different vertical planes, driving supports with which 50 the inclined bearing surfaces coöperate on the horizontal, and driving supports with which the horizontal bearing surfaces coöperate on the incline.

35. In a device of the class described, the combination with steps or carriers, of driving members constituting a way having horizontal and inclined portions, and means for carrying the steps from one of said portions to the other.

36. In a device of the class described, the combination with steps or carriers, of driving members constituting a way having horizontal and inclined portions, and a rotating member for carrying the steps from 65 the incline to the horizontal.

37. In a device of the class described, the combination with steps or carriers, of driving members constituting a way having horizontal and inclined portions, and a rotating cam for transferring the steps from 70 the incline to the horizontal.

38. In a device of the class described, the combination with a way having inclined and horizontal portions, of steps adapted to the way, means for driving the steps, and a cam 75 for transferring the steps from one portion of the way to the other.

39. In a device of the class described, the combination with the steps or carriers, of the driving members forming horizontal and 80 inclined tracks therefor, and means for carrying said steps from the driving members located on the incline over to the driving members located on the adjacent horizontal portion.

40. In a device of the class described, the combination with the steps or carriers, of the driving members forming horizontal and inclined tracks therefor, and means for carrying said steps from the driving members 90 located on the incline over to the driving members located on the adjacent horizontal portion consisting of a suitably located cam rotated in synchronism with the driving members and coöperating with the steps substantially as shown and described.

41. In a device of the class described, the combination with the steps or carriers having the vertical slots and pins, the pins of one step coöperating with the slots of the 100 adjacent step, of the driving members for said steps constituting the tracks.

42. In a device of the class described, the combination with the steps or carriers having the vertical slots and pins, the pins of one step coöperating with the slots of the adjacent step, of the plurality of rotating driving members for said steps constituting the tracks thereof.

43. In a device of the class described, a 110 series of moving steps having slot and pin connections, and driving members for said steps constituting the supports therefor.

44. In a device of the class described, the combination with the steps or carriers having the vertical slots and pins at the ends, the pins of one step coöperating with the slots of the adjacent step, of the plurality of driving members for said steps constituting the tracks thereof and arranged on 120 different angles so that the steps form horizontal landings and inclined stairs, and means for moving said driving members at the proper relative rates of speed throughout the different portions of the course.

45. In a device of the class described, the combination with the steps or carriers having the vertical slots and pins at the ends, the pins of one step coöperating with the 125 slots of the adjacent step, of the plurality 130 of driving members for said steps constituting the tracks thereof.

- of driving members for said steps constituting the tracks thereof and arranged at different angles so that the steps form horizontal landings and stairs, a single source 5 of driving power, and connections between said source of driving power and the driving members whereby they are driven at different rates of speed on the different angles for the purpose described.
- 10 46. In a device of the class described, ways arranged to provide inclined and horizontal runs, steps adapted to move thereon and arranged to form inclined stairs and horizontal landings, connections between the steps 15 to present their treads horizontal and uppermost on the landings and incline, and means for driving the steps at different speeds on the different portions of the way, the horizontal component of which will be the same 20 on the inclined and horizontal portions, the driving means constituting the step-supports.
47. In a device of the class described, the combination with a continuous chain of steps arranged to produce stairs on the incline and a landing on the horizontal, of connections between said steps to form them in a continuous chain with their treads horizontal, and driving mechanisms for moving the steps at different speeds on the different 25 portions and so that the horizontal component thereof will be the same on the inclined and horizontal portions, the driving means constituting the step-supports.
- 30 48. In a device of the class described, the combination with the steps arranged to constitute the stairs on the inclined portions and the horizontal landings, of the driving members for said steps constituting the tracks thereof, and means for operating said members at such relative rates of speed on the different portions that the horizontal component of speed will be the same whether on the inclined or horizontal portions.
- 35 49. In a device of the class described, a way having angularly disposed portions, steps adapted to the way, and means for driving the steps on each of such portions of the way but at different speeds the horizontal component of which is the same.
- 45 50. In a device of the class described, a way having horizontal and inclined portions, steps traveling on the way, connections between the steps to hold their treads horizontal, and direct driving members 55 cooperating with the steps on the inclined and horizontal portions and imparting motion at different speeds the horizontal component of which is the same, the driving members constituting the step-supports.
- 60 51. In a device of the class described, a way having horizontal and inclined portions, steps traveling on the way, a driving member coöperating with the steps on the incline and a driving member coöperating with the steps on the horizontal, such members moving the steps at different speeds, the horizontal component of which is the same on the horizontal and the incline. 65
52. In a device of the class described, a way consisting of inclined and horizontal portions, and a series of steps having straight risers, and connections between the steps to hold the treads horizontal and maintain the risers in contact with adjacent steps throughout the transporting run, and direct driving connections for the steps of the conveying run, the driving means constituting the step-supports. 70
53. In a device of the class described, a way consisting of inclined and horizontal portions, a series of driven steps, and pin and slot connections between the steps to maintain the riser of each thereof substantially in contact with the tread of an adjacent step throughout the transporting run, 75 and direct driving connections for the steps of the conveying run, the driving means constituting the step-supports. 80
54. In a device of the class described, a way having angularly disposed portions, a series of driven steps traveling on the way, and connections between the steps holding them in position with their treads horizontal on the different portions of the way and in contact with the riser of an adjacent step 85 and permitting them to move vertically as they pass therebetween, and direct driving connections for the steps of the conveying run, the driving means constituting the step-supports. 90
55. In a device of the class described, a way having inclined and horizontal portions, a series of driven steps traveling on the way, and connections between the steps consisting of a vertical slot in one step and a projection on an adjacent step adapted to the slot, whereby the steps are adapted to move vertically as the steps pass to and from the inclined portion to maintain the riser of each step in contact with the tread of the adjacent step throughout the transporting run, and direct driving connections for the steps of the conveying run, the driving means constituting the step-supports. 100
56. In testimony whereof I affix my signature 105 in presence of two witnesses.
